OVERHEAD DOOR OPERATING MECHANISM

Edgar N. Rosenberg, Salt Lake City, Utah

Application April 21, 1944, Serial No. 532,080

8 Claims. (Cl. 20—19)

1

This invention relates to an overhead door operating mechanism particularly useful and desirable in garages, warehouses, and the like.

A further object of this invention is to provide an operating mechanism especially suitable for a one-piece door for moving it between a weather-tight fit against its door frame and an overhead position opening the doorway.

A further object of this invention is to provide an operating mechanism for rolling a one-piece door to an overhead position in one motion, while the door rotates through a right angle from an upright position against the door frame to a substantially horizontal position above the door opening.

Still a further object of this invention is to provide a door operating mechanism wherein the door can be perfectly counterbalanced throughout its travel, or can be slightly over or underbalanced, as desired, so it can be moved automatically in one direction by merely releasing a latch, possibly by remote control from a distance, such as by radio, photo-electric cell, or distant switch, and can be moved in the other direction by a slight amount of force, either manual or by power.

Yet a further object of this invention is to a door operating mechanism that can be supported almost completely on the door frame.

Still a further object of this invention is to provide a door operating mechanism that will move the door bodily away from the door frame as it commences to open, thus eliminating the possibility of jamming or binding, and which will move the door bodily toward and against the door frame as it comes to closed position, thus insuring a tight fit thereagainst.

Yet a further object of this invention is to provide a door operating mechanism that will maintain the door parallel to the door frame for a short distance, as it commences the opening, eliminating the possibility of the rollers binding in the tracks.

A further object of this invention is to provide a trackway forming part of a door operating mechanism which can be easily manufactured and installed in operative position on a door frame.

Still a further object of the invention is to provide a door operating mechanism trackway which includes one pair of straight or slightly curved parallel tracks, and a second pair of somewhat curved yet parallel tracks, wherein preferably the straight or slightly curved pair of tracks are designed to serve as the weight carrying

2

tracks and the curved pair of tracks are designed to serve as the guide tracks, and wherein both pairs of tracks are joined together as a unit, yet can pass the door rollers therealong past the joining means of the tracks without interference.

With the foregoing and other objects in view, as will hereinafter become apparent, this invention comprises the combinations, constructions, and arrangements of parts hereinafter set forth, disclosed, claimed, and illustrated in the accompanying drawings, wherein:

Fig. 1 is a side elevational view of the door and its operating mechanism, with the door in closed position in full lines, and in open position in dot-dash lines.

Fig. 2 is a detail view, on a larger scale, of the pivot arm, pintle, and associated parts.

Fig. 3 is a view at right angles to Fig. 2.

Fig. 4 is a perspective view of the parallel motion and counterbalancing mechanism.

Fig. 1A is a view similar to Fig. 1, of a slightly modified form of this invention.

Figs. 2A and 3A are views corresponding to Figs. 2 and 3, and

Fig. 1B shows a form with slightly curved weight carrying tracks.

In the following description, identical reference numbers are used to denote identical parts throughout the various views in both forms of the invention, and corresponding but slightly different parts are indicated by primed numbers.

There is shown at 1 a conventional rectangular door frame having the usual door opening which is to be closed by an overhead one-piece door 2. This door 2 is movable between the closed position shown in full at 2 and the up or open position shown in dot-and-dash line position at 20 by means of the door operating mechanism of this invention. Firmly secured to the opposite sides of the door 2 at about its center line of gravity are the pintles 3. Inasmuch as the pintles 3 carry the weight of the door 2, and impart rotary motion to the door of about a right angle as it is moved between the open and closed position, the securing means should be very firm, and is here shown as including a plate 21 to which the pintle is welded as at 22, and the securing means also includes bolts 23 and 24 through the pintle 3 and the plate 21 to the door 2. At their extreme outer ends, the pintles 3 are provided with flanged wheels 4 or 4' rotatably secured thereon so as to be located between the weight carrying parallel straight upper and lower tracks 5 or parallel curved tracks 5'. Rollers 6 are jour-

naled between guide tracks 7 or 7' on the pivot arms 8 or 8'.

The tracks 5 or 5' and 7 or 7' are secured in proper spaced relation to each other by the fastening plates 9 and 10 or 9' and 10'. In Figs. 1, 2 and 3, the pivot arms 8 are angular as shown, while the fastening plates 9 and 10 are straight bars, suitably secured to each of the tracks. In Figs. 1A, 2A and 3A, the pivot arms 8' are straight bars, and the fastening plates 9' and 10' are shaped like a rectangle. As a result of such construction, the rollers 6 and the wheels 4 can travel along their trackways without hindrance, yet the tracks are securely fastened in position and kept in proper relation to each other. The lower ends of the tracks are each securely bolted to the door frame 1 and the upper ends are secured by means of their plates 9 or 9' and the brackets 11 or 11' to the top of the door frame 1, thus making the device independent of the location of a ceiling, should the ceiling of the garage or the warehouse be too high to be convenient or accessible.

As the door is moved along the tracks 5 between the open and closed positions, the pivot arms 8 or 8' will cause the door 2 to rotate through a right angle as the rollers 4 move along the guide tracks 7 or 7'. The operating mechanism for causing and controlling this motion between the open and closed position is shown in Fig. 4. The operating mechanism includes a shaft 12 provided with sheaves 13 and journaled in bearings in brackets 14 suitably mounted, as shown in Fig. 1 on the bottom of the upper end of the lower tracks 5. Also securely fastened to the shaft 12 is one or more additional sheaves 15. Control cords 16 are passed several times about the sheaves 13, and the pulleys 17 at the lower ends of lower tracks 5 are tied to swivel plates 18, the swivel plates 18 being swiveled on the pintles 3 between suitable spacing washers 25. A cable 19 passed about the sheave 15 holds a counterbalancing weight W. Obviously, instead of gearing the cords 16 to sheaves 13 as above, sprockets 17 and a chain may be substituted for the sheaves 13 and pulleys 16.

In operating, the weight W may be such as to exactly counterbalance the door 2, or it may be slightly more or less than the weight of the door, depending on whether it is desired to move the door in both directions with the slightest effort, or whether all the effort is to be used in moving it in one direction, and letting gravity move it in the other direction. With the control cords 16 in effect geared to the sheaves 13, the swivel plates 18 will exert an equal force on both pintles 3, keeping the force equal on both pintles and moving them in a parallel motion, preventing any binding of the wheels against the tracks. As the door is moved away from the door-frame 1, the pivot arms 8 or 8', guided by their rollers 6 in the guide tracks 7 or 7', first rotate the door very slowly so that all parts of the door move definitely away from the door-frame, and the rotation of the door is controlled by the pivot arms so that the edges of the door can never touch the door-frame once it starts to move. Thereafter, the curved tracks 7 or 7' cause the pivot arms to rotate the door until it has completed a right angle just as it approaches the top open position 20. The curved tracks are desirable when the ceiling is low or the available overhead space is very limited, for the curved tracks 5 serve to keep

the top of the door somewhat lower during its travel than the straight tracks do.

While the device has been shown and the structure described in detail, it is obvious that this invention is not to be considered limited to the exact form disclosed, and that changes may be made therein, within the scope of what is claimed, without departing from the spirit of the invention.

Having thus set forth and disclosed the nature of this invention, what is claimed is:

1. An overhead door construction comprising in combination with a door and a door-frame having an opening narrower than the door, a pair of pintles adapted to be secured to the door at the opposite ends of approximately its center line of gravity, a wheel journaled at the outer end of each pintle, track means adapted to be secured to the frame of the door to extend angularly upwards, a second track means secured in fixed crossed relation to said first mentioned track means, said wheels being adapted to travel along one of said track means, a pivot arm fixed to each pintle, and a guide roller journaled on each pivot arm and guided along the other track means, said second track means being at such angle to said first track means as to cause said pivot arms to pivot said pintles and the door to which they are secured to rotate approximately a right angle as said door is moved from a closed position flat against its frame to an open overhead position.

2. An overhead door construction comprising in combination with a door and a door-frame having an opening narrower than the door, a pair of pintles adapted to be secured to the door at the opposite ends of approximately its center line of gravity, a wheel journaled at the outer end of each pintle, track means adapted to be secured to the frame of the door to extend angularly upwards, said wheels being adapted to travel along said track means, a guide track means secured in fixed crossed relation to said first mentioned track means, a pivot arm fixed to each pintle, and a guide roller journaled on each pivot arm and guided in said guide track means, said guide track means being fixed at such angle to said wheel track means as to cause said pivot arms to pivot said pintles and the door to which they are secured to rotate approximately a right angle as said door is moved from a closed position flat against its frame to an open overhead position.

3. An overhead door construction comprising in combination with a door and a door-frame having an opening narrower than the door, a pair of pintles adapted to be secured to the door at the opposite ends of approximately its center line of gravity, a wheel journaled at the outer end of each pintle, weight carrying track means adapted to be secured to the frame of the door to extend angularly upwards, said wheels being adapted to travel along said track means, a guide track means secured in fixed crossed relation to said weight carrying track means, a pivot arm fixed to each pintle, and a guide roller journaled on each pivot arm and guided in said guide track means, said guide track means being curved at such angle to said wheel track means as to cause said pivot arms to pivot said pintles and the door to which they are secured to rotate approximately a right angle as said door is moved from a closed vertical position flat against its frame to an open overhead approximately horizontal position and vice versa.

4. An overhead door construction comprising in combination with a door and a door-frame having an opening narrower than the door, a

pair of pintles adapted to be secured to the door at the opposite ends of approximately its center line of gravity, a wheel journaled at the outer end of each pintle, track means adapted to be secured to the frame of the door to extend angularly upwards, a second track means secured in fixed crossed relation to said first mentioned track means, said wheels being adapted to travel along one of said track means, a pivot arm fixed to each pintle, and a guide roller journaled on each pivot arm and guided along the other track means, said second track means being at such angle to said first track means as to cause said pivot arms to pivot said pintles and the door to which they are secured to rotate approximately a right angle as said door is moved from a closed position flat against its frame to an open overhead position.

5. An overhead door construction comprising in combination with a door and a door-frame having an opening narrower than the door, a pair of pintles adapted to be secured to the door at the opposite ends of approximately its center line of gravity, a wheel journaled at the outer end of each pintle, track means adapted to be secured to the frame of the door to extend angularly upwards, said wheels being adapted to travel along said track means, a guide track means unitarily secured to said first mentioned track means in crossed relation thereto, a pivot arm fixed to each pintle, a guide roller journaled on each pivot arm and guided in said guide track means, said guide track means being at such angle to said wheel track means as to cause said pivot arms to pivot said pintles and the door to which they are secured to rotate approximately a right angle as said door is moved from a closed position flat against its frame to an open overhead position.

6. In an overhead door track for door-frames and a door of a width greater than the width of the opening in the door-frame for closing against said door-frame, track units each embodying track members adapted to be extended inwardly and angularly upwardly from the door-frame from a point slightly below midway the height of the door and a second track means adapted to be extended inwardly and upwardly from the door-frame from a point slightly spaced from said first-mentioned point across said first-mentioned track means, and means securing said track means to each other in fixed relation to each other in slightly spaced but parallel planes.

7. In an overhead door construction for door-frames a door of a width greater than the width

of the opening in the door-frame for closing against said door-frame, track units mounted at opposite sides of the door-frame each embodying track members extending inwardly and angularly upwardly from the door-frame from a point slightly below midway the height of the door and a second track means extending inwardly and upwardly from the door-frame from a point slightly spaced from said first-mentioned point across said first-mentioned track means, means securing said track means to each other in fixed relation to each other in slightly spaced but parallel planes, a pair of pintles secured to the door at approximately its center line of gravity, a wheel journaled at the outer end of each pintle for travel along said first-mentioned track means, a pivot arm fixed to each pintle, and a guide roller journaled on each pivot arm for travel along said second-mentioned track means to thereby turn the door between a vertical closed position against the door frame and a horizontal open position away from and above the door-frame opening as the pintle-journaled wheels travel along said first-mentioned track means.

8. In an overhead door construction for door-frames, a door of a width greater than the width of the opening in the door-frame for closing against said door-frame, track units mounted at opposite sides of the door-frame each embodying track members extending inwardly and angularly upwardly from the door-frame from a point slightly below midway the height of the door and a second track means extending inwardly and upwardly from the door-frame from a point slightly spaced from said first-mentioned point across said first-mentioned track means, means securing said track means to each other in fixed relation to each other in slightly spaced but parallel planes, bracket means extending horizontally from the top of the door-frame to which the upper ends of said track means extend, a pair of pintles secured to the door at approximately its center line of gravity, a wheel journaled at the outer end of each pintle for travel along said first-mentioned track means, a pivot arm fixed to each pintle, and a guide roller journaled on each pivot arm for travel along said second-mentioned track means to thereby turn the door between a vertical closed position against the door-frame, and a horizontal open position away from and above the door-frame opening as the pintle-journaled wheels travel along said first-mentioned track means.
